UNITED STATES PATENT OFFICE.

CUTHBERT RITSON, OF BLYTH, ENGLAND.

CARGO VESSEL.

Application filed July 27, 1926, Serial No. 125,230, and in Great Britain August 5, 1925.

This invention relates to cargo vessels, and has for its object to provide an improved construction of cargo vessel whereby the cargo-carrying capacity of the vessel is increased as compared with a vessel of the same moulded dimensions constructed according to existing shipbuilding practice, the increased cost of construction being more than compensated for by the augmented earning power, increased utility and greater seaworthiness and strength of my improved vessel.

According to my invention I provide a fore-and-aft deck rising from the upper deck having inwardly inclined sides above the upper deck which confine the upper portions of the holds in a fore-and-aft direction, said inclined sides supporting and elevating the coamings of the hatchways substantially above the deck to increase the cargo spaces.

The plating of the inclined sides is supported by inclined beams which are separate from but strongly connected to the usual side framing of the vessel and at their upper ends to the outsides of the hatch coamings. Platforms are provided as usual between and at the ends of each set of hatchways. Fore-and-aft gangways are provided along the sides of the hatchways supported by structural members which follow the internal contour thereof and are separate from but connected to the inclined beams and to the hatch coamings, the inclined plating of the sides of the deck erection being continued over the gangways and platforms.

A 'thwartship tank is disposed between each pair of elevated hatchways, said tank having upwardly diverging sides which confine the upper portions of the holds in a 'thwartship direction and extend up to the elevated hatch coamings, the ends of said tank being closed above the upper deck by the inclined sides of the deck erection and below said deck by the sides of the vessel.

The 'thwartship tanks may extend both above and below the upper deck of the vessel. A 'thwartship tank may also be provided at the end of each set of hatchways, one side of said tank being inclined towards the hatchways and extending up to the elevated hatch coamings. The angle of inclination of the sloping sides of the deck erection and of the 'thwartship tanks is approximately that of the angle-of-rest of the cargo for which the vessel is intended (which may be

grain, coal, coke or other bulk cargo), and the hatchways are raised by said sloping sides above their customary level thus providing additional cargo space to an amount which exceeds the loss of space due to the 'thwartship tanks, where these are fitted. The additional buoyancy obtained by the deck erection enables the freeboard of the vessel to be reduced and the deadweight to be correspondingly increased.

Fore-and-aft side tanks may be fitted if desired, said side tanks being disposed below the upper deck and externally of the inclined sides of the deck erection, and, where said fore-and-aft tanks extend across the 'thwartship tanks, the ends of the latter below the upper deck are closed by said side tanks. The side tanks may however stop at the 'thwartship tanks.

The portions of the 'thwartship tanks above the upper deck may in some cases form deck erection spaces and be used for cargo spaces.

The cargo can be loaded in bulk into the holds of my improved vessel, and it will fill the cargo spaces without it being necessary to trim the cargo except to level it off flush with the top of the hatch coamings or so much below same as may be desirable.

I will further describe my invention with reference to the accompanying drawings wherein Figure 1 is a central longitudinal section and Figure 2 a deck plan of a single-deck cargo vessel according to my invention, Figure 3 is a transverse section thereof, the left-hand half in the way of a hatchway and the right-hand half in the way of a 'thwartship tank, and Figures 4 and 5 are respectively a part longitudinal section and a part transverse section, to a larger scale, illustrating the internal construction of a 'thwartship tank therein. Figure 6 is a part similar view to Fig. 3 illustrating a modified construction in which the vessel is fitted with fore-and-aft side tanks, and Figure 7 is a transverse section in the way of a hatchway of a 'tween deck vessel, the left-hand half showing the vessel without side tanks and the right-hand half showing the vessel fitted with side tanks. Figure 8 is a part similar view to a larger scale of the left-hand half of Fig. 7 illustrating a detail, and Figure 9 is a section on the line X—Y therein.

Referring to the said drawings, in the single-deck cargo vessel illustrated in Figs. 1 to 5

- 1 to 5, *a* are the 'thwartship tanks which are provided between the hatchways *b* and at the fore and after ends thereof, said tanks extending both above and below the upper deck *c*. The plating *d* separating the tanks *a* from the upper portions of the holds *e* is inclined approximately according to the angle-of-rest of the cargo for which the vessel is intended. The internal construction 5 of the 'thwartship tanks is best shown in Figs. 4 and 5. The plating *d* is attached at the top to the bottoms of the hatch coamings *b*¹ and is strengthened by inclined frames *d*¹. At the bottoms of the tanks, the 10 frames *d*¹ and plating *d* are attached by brackets *d*² to hold beams *f* which are connected by brackets *f*¹ to web frames *g* at the sides of the vessel. The tanks *a* are stiffened by a lattice work of bars and brackets *a*¹. 15 20 At the top, the 'thwartship tanks are closed in by platforms *h* between the hatchways *b* and at the fore and after ends thereof, said platforms providing the necessary space and support for the usual deck machinery and 25 fittings.

The fore-and-aft deck erection is formed by plating *j* carried by inclined frames *j*¹, the bottoms of which are bent horizontally and attached by brackets *j*² to the side 30 frames *k* of the vessel. The tops of the frames *j*¹, in the way of the hatchways, are connected to the bottoms of the hatch coamings *b*¹, and, in the way of the 'thwartship tanks, they are connected by brackets *j*³ to the platforms *h*. The plating *j* and framing *j*¹ are inclined approximately according 35 to the angle-of-rest of the cargo for which the vessel is intended. The plating *j* is connected to the upper deck plating *c* by fore-and-aft angle bars *c*² (Fig. 4).

At the sides, the 'thwartship tanks *a* are closed by the inclined plating *j* above the upper deck *c*, and by the side plating *k*¹ of the vessel below said deck.

45 The frames *j*¹ also carry top bars *m*¹ supporting fore-and-aft gangways *m* which run along the sides of the hatchways *b* and platforms *h* to meet the forecastle bulkhead *n*¹, the fore bridge deck bulkhead *n*², the after 50 bridge deck bulkhead *n*³ and the poop bulkhead *n*⁴, the plating of the gangways being carried down as shown to meet the plating *j* and forming an integral portion of the deck erection which is stiffened in the fore-and-aft direction by said gangways. 55 Brackets may be substituted for or provided in addition to the bars *m*¹.

If desired, and as illustrated in Fig. 6, the vessel may also be provided with fore-and-aft side tanks *p* below the upper deck *c* and outside of the inclined sides *j* of the deck erection, said side tanks being formed by downwardly extending the inclined side plating *j* and frames *j*¹. The side tanks *p* 60 65 may stop at the 'thwartship tanks *a*, in

which case the construction in the way of a 'thwartship tank is as shown in the right-hand half of Fig. 3, or the side tanks may be continued past the 'thwartship tanks, in which case the construction is as shown in 70 the right-hand half of Fig. 6, the 'thwartship tanks being closed by the extended inclined plating *j*.

Where the vessel is double-decked and is provided with 'tween decks *q* or a long 75 bridge deck as illustrated in Fig. 7, the construction, whether without side tanks (left-hand half) or with side tanks (right-hand half), is substantially the same as that above described in connection with a single-decked ship. The inclined side plating *j* entirely separates the main holds *e* from the 'tween decks, means of access to the latter being obtained by fitting extra independent hatchways *q*¹ in the deck *r*. Sliding doors *s* (Figs. 8 and 9) are provided in the plating *j* adapted to be raised and lowered, when required, by suitably mounted gearing *s*¹ from the deck *r* to open and close the 'tween decks, whereby cargo in the 'tween decks 80 85 90 95 can be discharged into the main holds.

Access to portions of the 'thwartship tanks *a* above the upper deck *c* may be provided for by manholes or hatchways in the platforms *h*, in which case the portions of 95 said tanks below the deck *c* will be sealed from the upper portions, but in the case of heavy cargoes such as iron ore, the whole of the 'thwartship tanks may be sealed to obtain additional buoyancy.

By way of illustration of the advantages of my improved construction, I will take as an example a cargo vessel of the type illustrated in Figs. 1 and 2 having moulded dimensions of 245 feet by 37 feet 6 inches 105 by 19 feet 6 inches, and a deadweight of approximately 2300 tons. Without in any way altering the moulded dimensions of this vessel, I adapt it to embody my invention by positioning the hatchways in the fore-and-aft and in the 'thwartship directions so as to give the desired angle of the sloping sides of the deck erection and 'thwartship tanks, and I make these hatchways about 5 feet 6 inches above the upper deck as compared with the customary practice of disposing the hatchways level with the deck. I then carry the sloping sides of the 'thwartship tanks below the upper deck to a depth of about 110 115 120 125 130 3 feet 6 inches.

If I fit one 'thwartship tank between Nos. 1 and 2 hatchways and one between Nos. 3 and 4 hatchways, the capacity of the holds is reduced by about 65 tons. Moreover it will be found necessary in this particular vessel, in order to obtain the required angle of slant of the ends of the holds, to move the forward bulkhead *n*¹ one frame space further aft than is usually done and the boiler room bulkhead *n*² one frame space forward. 130

This causes a further reduction in the capacity of the holds of about 20 tons.

To compensate for this loss and to gain the increased earning power hereinbefore mentioned, I make the superstructure above the deck *c* of a capacity, after allowing for the above deductions, of about 160 tons, which amount includes the weight of the extra material used. This additional dead-
10 weight is permitted owing to the increased buoyancy and the consequently reduced free-board obtained, which reduction in this case is about 9½ inches.

A cargo vessel with its upper structure arranged and constructed as herein described is completely self-trimming; bulk cargo, such, for example, as coals or grain, filling close up to the walls of the inclined upper portions of the holds as it is loaded and requiring only to be levelled off at the hatch coamings, the vessel thus requiring less time for loading and discharging with a consequent saving in expense over existing types of vessels of similar moulded dimensions.
25 There are few obstructions in the holds and hence less likelihood of damage when grabs are used. Stowage of the cargo is facilitated, and possibility of the cargo shifting in bad weather is minimized.

30 The sea-worthiness and strength of the vessel are increased by reason of the additional buoyancy and other advantages due to the inclined sides and 'thwartship tanks which form a superstructure higher than the usual hatch coamings. Less water will lodge on the deck in bad weather and it will be more quickly cleared off, thus reducing strains on the deck and possibility of damage. The raised gangways *m* provide safe
40 and easy passage to-and-fro on the ship.

In the case of a 'tween deck vessel or one having a long bridge deck, the 'tween deck portions *q* can be made without hatchways to the 'tween deck at the sides which portions then form watertight compartments thus increasing the reserve buoyancy and decreasing net tonnage when heavy bulk cargoes are carried and adding to the sea-worthiness and safety factor of the vessel.
50 When the ship is in ballast, the tanks may be filled with water ballast to the required extent thus improving the behaviour and speed of the vessel under these conditions.

Greater strength is obtained in both fore-and-aft and 'thwartship directions by my system of construction, a strut being formed at the junction of the 'thwartship tanks *a* and the fore-and-aft inclined plating *j* of the deck erection as shown in dotted lines at
55 *x* in Fig. 2, which transmits in both directions simultaneously the stresses of heavy seas coming inboard, the structure forming a complete girder. The gangways *m*, in addition to providing additional buoyancy
60 and safety at sea, add considerably to the

strength, and the upper structure will stand more strain than in the existing types of cargo vessels.

What I claim as my invention, and desire to secure by Letters Patent is:—

1. In a cargo vessel, a fore-and-aft deck erection rising from the upper deck and having inwardly inclined sides above said deck which confine the portions of the cargo space above the deck in a fore-and-aft direction, hatch coamings supported by said inclined sides whereby the hatchways are elevated substantially above the deck to increase the cargo spaces, inclined beams supporting the plating of said inclined sides separate from but strongly connected to the usual side framing of the vessel and at their upper ends to the outsides of the hatch coamings, and platforms between and at the ends of each set of elevated hatchways.
70

2. In a cargo vessel, a fore-and-aft deck erection rising from the upper deck and having inwardly inclined sides above said deck which confine the portions of the cargo space above the deck in a fore-and-aft direction, hatch coamings supported by said inclined sides whereby the hatchways are elevated substantially above the deck to increase the cargo spaces, inclined beams supporting the plating of said inclined sides separate from but strongly connected to the usual side framing of the vessel and at their upper ends to the outsides of the hatch coamings, platforms between and at the ends of each set of elevated hatchways, fore-and-aft 100 gangways along the sides of said hatchways, and structural members supporting said gangways and following the internal contour thereof, said structural members being separate from but connected to the inclined 105 beams and to the hatch coamings, the inclined plating of the sides of the deck erection being continued over the gangways and platforms.

3. In a cargo vessel, a fore-and-aft deck 110 erection having inwardly inclined sides above the upper deck which confine the upper portions of the holds in a fore-and-aft direction, hatch coamings supported by said inclined sides whereby the hatchways are 115 elevated substantially above the deck to increase the cargo spaces, platforms between and at the ends of each set of elevated hatchways, means for stiffening said deck erection in the fore-and-aft direction, a 'thwartship tank between each pair of elevated 120 hatchways, said tank having upwardly diverging sides which confine the upper portions of the holds in a 'thwartship direction and extend up to the elevated hatch coamings, the ends of said tank being closed above the upper deck by the inclined sides of the deck erection and below said deck by the sides of the vessel.
125

4. In a cargo vessel, a fore-and-aft deck 130

erection having inwardly inclined sides above the upper deck which confine the upper portions of the holds in a fore-and-aft direction, hatch coamings supported by said inclined sides whereby the hatchways are elevated substantially above the deck to increase the cargo spaces, platforms between and at the ends of each set of elevated hatchways, and means for stiffening said deck 10 erection in the fore-and-aft direction, a 'thwartship tank between each pair of elevated hatchways, said tank extending both above and below the upper deck of the vessel, and having upwardly diverging sides 15 which confine the upper portions of the holds in a 'thwartship direction and extend up to the elevated hatch coamings, the ends of said tank being closed above the upper deck by the inclined sides of the deck 20 erection and below said deck by the sides of the vessel.

5. In a cargo vessel, a fore-and-aft deck 25 erection having inwardly inclined sides above the upper deck which confine the upper portions of the holds in a fore-and-aft direction, hatch coamings supported by said inclined sides whereby the hatchways are elevated substantially above the deck to increase the cargo spaces, platforms between 30 and at the ends of each set of elevated hatchways, and means for stiffening said deck erection in the fore-and-aft direction, a 'thwartship tank between each pair of elevated hatchways, and a 'thwartship tank at 35 the end of each set of hatchways, at least one side of each of said tanks extending up

to and being inclined towards the hatch coamings, said inclined sides confining the upper portions of the holds in a 'thwartship direction, the ends of said tanks above the upper deck being closed by the inclined sides of the deck erection and below said deck by the sides of the vessel. 40

6. In a cargo vessel, a fore-and-aft deck 45 erection having inwardly inclined sides above the upper deck which confine the upper portions of the holds in a fore-and-aft direction, hatch coamings supported by said inclined sides whereby the hatchways are elevated substantially above the deck to increase the cargo spaces, platforms between 50 and at the ends of each set of elevated hatchways, and means for stiffening said deck erection in the fore-and-aft direction, a 'thwartship tank between each pair of elevated hatchways, and a 'thwartship tank at 55 the end of each set of hatchways, at least one side of each of said tanks extending up to and being inclined towards the hatch coamings, said inclined sides confining the upper portions of the holds in a 'thwartship direction, the ends of said tanks above the upper deck being closed by the inclined sides of the deck erection and below said deck by the sides of the vessel, and fore-and-aft tanks disposed below the upper deck and externally of the inclined sides of the deck 60 erection. 65

In testimony whereof, I affix my signature.

CUTHBERT RITSON.
